BY R. R. THEIS.

Geo. P. Kimmel ATTORNEY.

UNITED STATES PATENT OFFICE.

LESLIE G. ANDREWS AND RAYMOND R. THEIS, OF LINCOLN, NEBRASKA.

KEY HOLDER.

Application filed December 28, 1921. Serial No. 525,415.

To all whom it may concern:

Be it known that we, LESLIE G. ANDREWS and RAYMOND R. THEIS, citizens of the United States, residing at Lincoln, in the county of Lancaster and State of Nebraska, have invented certain new and useful Improvements in Key Holders, of which the following is a specification.

This invention relates to key holders and has for one of its objects to simplify and improve the construction and increase the efficiency and utility of devices of this character.

With this and other objects in view, the invention consists in certain novel features of construction as hereinafter shown and described and then specifically pointed out in the claim, and in the drawings illustrative of the preferred embodiment of the invention:

Figure 1 is a side elevation of the improved device closed.

Fig. 2 is a side elevation of the improved device in open position.

The improved device includes a casing or folder preferably formed from leather or the like and folded intermediate the side edges along the line 10 as shown in Fig. 2, to form a rear or back member 12 and a front or cover member 11, and detachably coupled by one or more "snaps" or glove fasteners indicated at 13.

Attached to the back member 11 of the folder is a casing or shell 14 a flexible winding element such as a chain, a portion of which is represented at 15.

Attached to the outer or free end of the flexible element 15 is a key holding device preferably formed from a single section of wire bent into three portions, two straight portions 33 and 34 in parallel relation and a third portion bent into a plurality of key receiving loops 35. The portions 33 and 35 are connected at one end by a curved portion 36 and the adjacent end of the portion 34 is spaced from the curved portion, as shown. The opposite ends of the portions 34 and 35 are coupled by an eye 38 to receive the outer link 37 of the chain 15. The free end of the portion 33 of the key holder is preferably curved away from the member 34, to provide an easy means for inserting the looped ends of the keys.

To insert the keys, the latter are threaded

by their eyes upon the portion 33 and around the larger loop 36 and then consecutively into the loops 35, each of the latter being designed to hold a key, as illustrated in Fig. 2.

The keys are thus held in separated condition, and each independently accessible as required, and held from accidental displacement by the yieldable portion 34.

A holding hook 39 is attached to the portion 12 of the folder, to retain the key holder in position when the folder is closed.

The keys are thus entirely concealed within the folder, which resembles an ordinary flat purse, and may be carried in the pocket without inconvenience.

The keys are not only protected from moisture from the body, but the material of the pockets are likewise protected from abrasion by the keys, and at the same time each key is readily and independently accessible.

When a key is required, it is only necessary to disconnect the snap 13, open the folder and withdraw the wire holder, the chain 15 permitting the wire holder to be removed bodily to permit the required key to be used.

The folder may be carried in the pocket, or mounted in any suitable manner upon a garment, for instance by loops indicated at 40 upon a strap 41, the latter attached in any suitable manner to the garment.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention, what is claimed as new is:

A key holder bent from a section of wire into three portions, two portions in parallel relation, and the third portion further bent into a plurality of spaced loops closed by the adjacent parallel member, the loops adapted to engage the eye portions of the keys and holding them in separated position.

In testimony whereof, we affix our signatures hereto.

LESLIE G. ANDREWS.
RAYMOND R. THEIS.
